TIE PLATE

Ernest L. Kidd, Glenhayes, W. Va.

Application November 2, 1942, Serial No. 464,229

1 Claim. (Cl. 238—299)

This invention relates to tie plates, and has for the primary object the provision of a device of this character which will provide safe and efficient securing of a rail on a wooden tie without driving spikes or like fasteners into the top face of the tie and thereby subjecting the tie to splitting or cracking from the top face thereof inwardly and thus eliminate the entrance of water or weather elements tending to rot or otherwise deteriorate the tie, consequently increasing the life of the tie materially.

Another object of the invention is the provision of a device of the above stated character which will provide a solid and even seat for the rail and will prevent lateral creeping thereof which eliminates the danger of rail spreading and accidents incident thereto and includes fasteners which are simple to install and remove and which will positively secure the rail on the device against displacement.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a fragmentary top plan view illustrating a tie plate constructed in accordance with my invention, and showing the application thereof to a rail and a wooden tie.

Figure 2 is an end elevation, partly in section, of the device applied to a wooden tie and supporting and securing a rail on the tie.

Figure 3 is a side elevation partly in section showing the device in applied position.

Figure 4 is a perspective view illustrating the device removed and minus the securing keys.

Figure 5 is a fragmentary top plan view showing the present invention applied to a tie and adapted to rails at their abutting ends and constructed to accommodate the usual fish plates for detachably connecting the adjacent ends of the rails.

Figure 6 is an end elevation showing the type of device illustrated in Figure 5 adapted to a tie and the adjacent ends of the rails.

Figure 7 is a transverse sectional view showing the device accommodating the fish plates.

Figure 8 is a perspective view illustrating one of the keys.

Referring in detail to the drawings, the numeral 5 indicates a fragmentary portion of a rail-

road rail and 6 a fragmentary portion of a wooden tie employed for the support and anchoring of the rail. It has been the customary practice to secure the rail 5 on the tie 6 by driving spikes or similar fasteners into the top face of the tie and into engagement with the base of the rail. This mode of securing the rail to the tie subjects the latter to having the top face split or cracked whence water and other weather elements may readily enter the tie and subject the same to rotting or other deterioration, naturally shortening the life of the tie and requiring the replacement thereof by another within a short period of time causing considerable expense as well as labor.

Through the use of the present invention, as shown in Figures 1 to 3, an efficient seat for the rail on the tie is provided and an effective securing means of the device to the tie as well as to the rail whence the top face of the tie will be free of having spikes or similar devices driven therein.

A tie plate 7 is provided which may straddle the tie, as shown in Figure 2, with the rail resting thereon and includes a top plate 8 and depending side portions 9 each cut away, as shown at 10, to reduce the use of material and provide a pair of attaching ears apertured, as at 11, to permit spikes 12 to pass therethrough and be driven into opposite vertical faces of the tie well below the top face of the tie. Prior to driving the spikes 12 into the tie by way of the openings 11, pointed metallic bearing strips 13 may be driven into the tie for the spikes 12 to engage and provide solid bearing surfaces for the spikes to press against when being driven into the tie and during the period of the use of the device.

It is preferable that the spikes be shaped, as shown in Figure 2, so that when being driven into the tie and against the walls of the openings 11 of the tie plate they will have a camming action resulting in tight wedging of the spikes in place.

The depending portions 9 of the tie plate 7 engaging opposite vertical walls of the tie and being anchored to the latter through the use of spikes will prevent the tie plate from shifting endwise of the tie.

Tines 14 are formed on the under face of the top wall 8 of the tie plate, so that when the latter is applied to the tie, as shown in Figure 2, said tines will bite into the tie and assist in preventing the misplacement or shifting of the tie plate on the tie. The tines being located on the under face of the top plate 8 and biting into the top face of the tie, will not admit water into the tie due to the tie plate resting flatly or evenly

upon the top face of the tie over where the tines bite into the tie.

Flat parallel spaced ribs 15 are formed on the top face of the wall 8 of the tie plate and form therebetween a seat for the base of the rail 5 by contacting opposite edges of the base which will prevent the rail from shifting laterally on the tie plate and the tie.

Integral with the ribs 15 and arranged opposite to each other are ears 16 provided with openings 17. The thickness of the ears 16 is much less than the width of the ribs 15 and extending transversely of the ribs 15 and base are parallel ribs 18, the spaces therebetween aligning with the openings 17. The top wall 8 of the tie plate is provided with openings 19 aligning with the openings 17 and the spaces between the ribs 18. Substantially L-shaped keys 20 are employed for securing the rail on the tie plate with the base of the rail positioned between the ribs 15 by said keys passing through the openings 17 to overlie the top faces of the base of the rail with the opposite angularly disposed ends of the keys seating with a wedging fit into the openings 19 of the tie plate. The keys being of L shape are formed each with a shank 21 and a laterally extending head 22. The head 22 tapers toward its free end so that when driven into the openings 19 of the tie plate, it will have a wedging action with the walls of the openings 19. The shank tapers on one face thereof, as shown at 23, to engage with the top face of the base of the rail.

The keys when applied, as shown in Figure 3, will effectively secure the base of the rail resting evenly on the tie plate between the ribs 15 against rising upwardly. The heads of the keys wedging into the openings 19 will prevent endwise shifting of the keys and the keys are prevented from rising upwardly so as to displace the heads from the openings 19 by the shanks of the keys wedging in the openings 17 of the ears 16. Any lateral shifting of the keys is further prevented by the ribs 18.

Thus it will be seen that the tie plate may be easily and quickly installed on a tie and secured thereto against displacement and will provide an efficient seat for the rail and when the keys are applied to the base of the rail with the base resting between the ribs 15 of the tie plate, the rail will be prevented from shifting laterally. The device secured to the tie as specified, eliminates driving of spikes or similar fasteners into the top face of the tie, consequently eliminating cracking of the top face of the tie and the admission of water and other weather elements tending to deteriorate the tie, resulting in longer life and use of the tie.

Referring to my modified form of invention as shown in Figures 5 to 7, inclusive, the tie plate is indicated in entirety by the character 24 and is similarly constructed to the tie plate 7 except the ribs 25 thereof have opposing faces stepped, as shown in Figure 7, to form seats 26 and 27. The seats with the top face of the tie plate 24

form a bearing surface for the bases of abutting rails and the seats 27 accommodate the fish plates 28 employed for coupling together the adjacent ends of the rails. The ribs 25 are otherwise constructed in accordance with the ribs 15 to receive the keys 20 which in this instance engage and partly overlie the fish plates, holding them firmly in seated position between the ribs 25 and consequently firmly securing the bases 10 of the rails on the tie plate.

The keys 20 when employed in the modified form of the invention have beveled faces 29 and the beveled faces 23 are omitted.

Either form of my invention heretofore described and shown in the drawings may be slightly modified for accommodating a guard rail frequently employed in connection with the main rails of a track by increasing the length of the tie plate and duplicating the seats and fastening 20 means thereon. When the device is used in conjunction with rails and their guard rails, misplacement of either kind of rails will be prevented and will permit the rails to be easily and quickly secured in place on a tie without mutilating and 25 damaging the top face of the tie and subjecting the tie to cracking inwardly from the top face.

While I have shown and described the preferred embodiment of my invention, it will be understood that minor changes in construction, 30 combination and arrangement of parts may be made without departing from the spirit and scope of the invention as claimed.

Having thus described my invention, what I claim is:

35 In a tie plate, a rigid elongated top plate resting on a top face of a tie and including projections to bite into said tie under said plate, depending portions integral with opposite edges of said plate and throughout the entire length of the top plate to engage opposite faces of the tie and each provided with openings and a cutout extending from a point below said top plate and opening outwardly through the lower edge of the depending portion, spikes driven into the tie by way of the openings, pointed metallic strips driven in the tie by way of the openings and engaged by the spikes during the latter's movement into the tie, ribs formed on the top plate transversely thereof and extending the full width of said plate and receiving a base of a rail therebetween, upstanding flanges formed on the ribs and provided with openings, spaced ribs formed on the first-named ribs and the flanges and extending transversely of the first-named ribs for the full width of the latter, said top plate having openings adjacent the second-named ribs, and L shaped keys wedged in the openings of the top plate and lying between the spaced ribs and having a tight fit therewith and extending through the openings of the flanges with a tight frictional fit therewith and engaging over the base of the rail.

ERNEST L. KIDD.
